Specification for Design.

Patented Jan. 8, 1918.

Application filed October 12, 1917. Serial No. 196,335. Term of patent 3½ years.

To all whom it may concern:

Be it known that I, WILLIAM HARRY GRINDLEY, a subject of the King of Great Britain and Ireland, residing at The Cedars, Stone, in the county of Stafford, have invented a new, original, and ornamental Design for Dishes, of which the following is a specification, reference being had to the accompanying drawing, forming part thereto.

I claim:

The design for a dish as shown.

WILLIAM HARRY GRINDLEY.
